SADIRON CONSTRUCTION

Howard A. Smith, St. Louis, Mo., assignor to
 Knapp-Monarch Company, St. Louis, Mo., a
 corporation of Missouri

Application January 12, 1937, Serial No. 120,217

16 Claims. (Cl. 219—25)

An object of my invention is to provide a sadiron construction of simple, durable and inexpensive construction.

5 A further object is to provide a comparatively inexpensive sadiron construction especially adapted for small, light weight irons, such as tourists irons, a novel terminal connection being provided and especially adaptable for a light weight iron of this character.

10 10 A further object is to provide a sadiron construction composed of a plurality of parts readily assembled relative to each other on a single stud of the sole plate.

15 15 A further object is to provide a terminal construction for sadirons comprising a terminal plate having a flange on which the terminal pins are mounted with the pins extending laterally relative to the iron.

20 20 Still a further object is to provide a guard for the terminal pins which effectively guards against accidental contact of the operator therewith and effectively encloses the terminal pins in such manner that a connector plug for association therewith can extend laterally from the iron without monopolizing the space behind the iron handle usually occupied by such connector plug.

25 25 With these and other objects in view, my invention consists in the construction, arrangement and combination of the various parts of the device, whereby the objects contemplated are attained, as hereinafter more fully set forth, pointed out in my claims and illustrated in the accompanying drawings, in which:

30 30 Figure 1 is a plan view of a sadiron construction embodying my invention.

Figure 2 is a rear end elevation of the same.

35 35 Figure 3 is a sectional view on the line 3—3 of Figure 1 showing the parts on a slightly enlarged scale.

40 40 Figure 4 is a plan view with the handle support broken off just above the shell, part of the shell broken away and all but the retaining ears of a guard for the terminal pins broken away.

45 45 Figure 5 is a perspective view of a terminal plate or bracket used in my sadiron construction.

Figure 6 is a perspective view of a handle support used therein.

50 50 Figure 7 is a side elevation of the rear end of the iron as seen from the left side thereof; and

55 55 Figure 8 is a side elevation from the right side showing most of the iron in section.

On the accompanying drawings I have used the reference numeral 10 to indicate a sole plate. The sole plate 10 is provided with a heating element groove 12 in which is mounted a heating element A. The element A may consist of a coiled resistance wire 14 embedded in argillous material 16. A single stud 18 extends upwardly from the sole plate 10.

60 60 A cover plate 20 is provided for retaining the

heating element A in position in the groove 12. This cover plate has a perforation indicated at 22 to receive the stud 18. A terminal bracket T is also mounted on the stud and the bracket T and plate 20 are retained in position by a nut 24. Above the nut 24 a spacer 26 is provided which is surmounted by a handle support HS.

5 5 A shell S is provided for enclosing the parts of the sadiron above the sole plate 10 and it is retained in position by a retainer nut 28. When 10 the nut 28 is tightened in position, it retains the shell S, the handle support HS and the spacer 26 tightly against the nut 24 and thus holds all the parts in assembled position.

10 10 The cover plate 20 is positioned on the sole 15 plate 10 and retained against rotation by a pair of lugs 30. The cover plate 20 is provided with notches 32 to receive these lugs. A third lug 34 is provided at the front end of the sole plate 10. All three of the lugs and the side edges of the plate 20 serve to position the shell S relative to the sole plate 10.

15 15 The heel or rear end of the shell S indicated at 25 25 36 is also positioned laterally by the rear terminal edge of the plate 20 which is preferably turned up in the form of a flange 38 fitting between the sides of the shell S. The portion of the plate 20 extending beyond the rear terminal edge of the sole plate 10 serves as a closure for the heel 36 of the shell S.

20 20 The terminal plate T has a foot portion 40 provided with a perforation 42 to receive the stud 18. Back of the foot portion 40 the terminal plate is offset upwardly and the major portion of the plate, indicated at 44, slopes rearwardly and 30 terminates in a tongue 46. The tongue 46 extends through a slot 48 in the plate 20 to retain the terminal plate T against rotation around the stud 18. The plate T has an upstanding flange 50 provided with a pair of perforations 52. Terminal pins 53 extend through the perforations 52 and are suitably insulated relative thereto and retained in position by nuts, as shown in Figure 3. A plurality of flanges 54 and 56 are provided on the flange 50 to reinforce it against bending. 45 Several ribs 58 are also provided on the terminal plate T for reinforcement purposes.

25 25 The flange 50, it will be noted by referring to Figures 3 and 4, extends fore and aft relative to the sole plate and slants slightly from the vertical. Accordingly the terminal pins 53 slant upwardly and outwardly relative to the sole plate. The shell S has an opening 60 for the flange 50 and the terminal pins 53. One edge of this opening is provided with a flange 62 slanting downwardly and inwardly (see Figure 3).

30 30 A guard G is provided for the terminal pins and the flange 50 which is arched over these parts and for ornamental purposes is made in a streamline shape as shown by dotted lines in Figures 1 60

and 4. The guard G has a plurality of tongues 64 for retaining it in position and encloses all but the outer ends of the pins 54. An inverted U-shaped flange 66 on the guard G defines an opening into which a connector plug 68 of a supply cord extends for coaction with the terminal pins 53.

The handle support HS is of the shape shown in Figure 6. In cross section it is channel shaped 10 and has a perforation at 70 receiving the stud and a downwardly extending sleeve of the retainer nut 28. The lower end of the handle support HS is mounted inside the shell S and extends upwardly through a channel shaped slot 15 72 therein (see Figure 4). The upper end is perforated as at 74 to receive a lag screw 76 extending into one end of a handle H. The handle may be of wood or any suitable composition.

The handle H has a rear face 78 which contacts with a bump or rib 80 formed on the handle support HS. Whenever there is ironing pressure on the handle H, it is transmitted to the rib 80 and this transforms the strain on the lag screw 76 from a bending strain to a tensioning strain, 25 thus providing a connection of the handle H to the sadiron, which is much longer lasting than the ordinary type.

Some changes may be made in the construction and arrangement of the parts of my device without departing from the real spirit and purpose of my invention, and it is my intention to cover by my claims any modified forms of structure or use of mechanical equivalents which may be reasonably included within their scope.

35 I claim as my invention:

1. In a sadiron construction, a sole plate, a shell therefor, a handle extending upwardly from said shell, terminals mounted on said sole plate back of said handle and extending sidewise from 40 said shell to coact with a connector plug, portions of the upper wall of said shell being adapted to form an elongated opening within which said terminals extend.

2. In a sadiron construction, a sole plate, a 45 shell therefor, a terminal plate mounted on said sole plate, a pair of terminals supported by said terminal plate and extending laterally from the sole plate, said shell having an opening for admitting a connector plug for association with said 50 terminals, a portion of said shell adjacent said opening being bent downwardly and inwardly to form one wall of said opening and to permit the inner lower corner of a connector plug to assume a countersunk position within the outline of said shell.

3. In a sadiron construction, a sole plate, a shell therefor, a terminal plate mounted on and supported entirely by said sole plate and having a terminal supporting portion extending in an 60 obliquely upward direction, a pair of terminals supported by said terminal supporting portion and extending laterally from the sole plate and an opening in said shell for admitting a connector plug for association with said terminals, 65 said shell at the bottom of said opening having a flange sloping downwardly and inwardly, said terminal supporting portion being located above the inner edge of said flange.

4. In a sadiron construction, a sole plate, a 70 shell therefor, a terminal plate mounted on and supported entirely by said sole plate, a pair of terminals supported by said terminal plate and extending laterally from the sole plate and an opening in said shell for admitting a connector 75 plug for association with said terminals, said ter-

minals sloping upwardly and outwardly through said opening, said shell having a countersunk portion in which said terminals are located and a guard over the upper sides of said terminals, said guard and said countersunk portion of said shell, 5 in conjunction with each other, constituting a reception socket for said connector plug.

5. In a sadiron construction, a sole plate, a shell therefor, a terminal plate, a pair of terminals supported by said terminal plate and extending laterally from the sole plate, means comprising a portion of said shell forming an opening in said shell for admitting a connector plug for association with said terminals and a guard for said terminals mounted on said shell, said guard arching from a position in front of the terminals and then over the terminals and terminating at a position behind them and forming, in conjunction with a portion of said shell, a single reception socket for both said terminals and a connector plug attachable thereto. 10 15 20

6. In a sadiron construction, a sole plate, a shell therefor, a terminal plate, a pair of terminals supported by said terminal plate, means forming an opening in said shell for admitting a connector plug for association with said terminals and a guard for said terminals mounted on said shell, said guard arching from a position at one side of the terminals and then over the terminals and terminating at a position on the opposite side of them, the side of said guard adjacent the bases of said terminals terminating at the shell and the opposite side being spaced therefrom so as to close the top of the opening and provide a side opening to permit such association of said connector plug with said terminals, said shell having a countersunk portion opposite said guard to partially receive said connector plug. 25 30 35

7. In a sadiron construction, a sole plate, a shell therefor and having its rear end overhanging the heel of said sole plate, a stud extending upwardly from said sole plate, a heating element for said sole plate, a cover plate for said heating element having a perforation receiving said stud, 45 a nut to retain said cover plate in position on said heating element, said shell having a perforation receiving said stud, a retainer nut for said shell threaded on said stud, said cover plate overhanging the heel of said sole plate and co-acting with said rear end of said shell to reinforce it and to provide a bottom closure therefor beyond the heel of said sole plate. 50 55

8. In a sadiron construction, a sole plate, a shell therefor, a stud extending upwardly from said sole plate, a heating element for said sole plate, a cover plate for said heating element, said shell having a perforation receiving said stud, a retainer nut for said shell threaded on said stud, a terminal bracket also mounted on said stud and having a pair of terminals mounted thereon and extending laterally therefrom, said terminal bracket having a projection and perforation connection with said cover plate at a point spaced from said stud to prevent rotation of the bracket 65 relative to the cover plate, said shell having an opening for admitting a connector plug to a position of association with said terminals. 60 65

9. In a sadiron construction, a sole plate, a shell therefor, a stud extending upwardly from said sole plate, a heating element for said sole plate, said shell having a perforation receiving said stud, a retainer nut for said shell threaded on said stud and a terminal bracket also mounted on said stud and having a pair of terminals 70 75 80 85 90 95

mounted thereon and extending laterally therefrom, said shell having an opening for admitting a connector plug to a position of association with said terminals, said shell at the bottom of said opening having a flange sloping downwardly and inwardly to the base of said terminals and the terminal supporting portion of said terminal bracket having a flange engageable beneath the sloping flange to hold it in position relative to 10 said terminals.

10. In a sadiron construction, a sole plate, a shell therefor, a stud extending upwardly from said sole plate, a heating element embedded in said sole plate, a cover plate for said heating element having a perforation receiving said stud, a nut to retain said cover plate in position retaining said heating element embedded in said sole plate, said shell having a perforation receiving said stud, a spacer between said nut and shell, a 20 retainer nut for said shell threaded on said stud and a terminal bracket also mounted on said stud and having a pair of terminals mounted thereon and extending laterally therefrom, said shell having a portion of the upper surface thereof forming a side of an opening for admitting a connector plug to a position of association with said terminals, said terminals sloping upwardly and outwardly through said opening, said shell having a countersunk portion in which said terminals are 25 located and a guard over the upper sides of said terminals, said guard and said countersunk portion of said shell, in conjunction with each other, constituting a reception socket for said connector plug.

35. 11. In a sadiron construction, a sole plate, a shell therefor, a stud extending upwardly from said sole plate, a heating element embedded in said sole plate, a cover plate for said heating element having a perforation receiving said stud, a nut to retain said cover plate in position retaining said heating element embedded in said sole plate, said shell having a perforation receiving said stud, a spacer between said nut and shell, a retainer nut for said shell threaded on said stud, a 40 terminal bracket also mounted on said stud and having a pair of terminals mounted thereon and extending laterally therefrom, said shell having a portion of the surface thereof forming one 45 side of the sloping wall of an opening for admitting a connector plug to a position of association with said terminals and a guard for said terminals mounted on said shell, said guard arching from a position in front of the terminals and then over the terminals and terminating at a 50 position behind them and forming in conjunction with a portion of said shell, a reception socket for a connector plug.

55. 12. In a sadiron construction, a sole plate, a shell therefor, a stud extending upwardly from 60 said sole plate, a heating element embedded in said sole plate, a cover plate for said heating element having a perforation receiving said stud, a nut to retain said cover plate in position retaining said heating element embedded in said sole plate, said shell having a perforation receiving said stud, a spacer between said nut and shell, a retainer nut for said shell threaded on said stud, a 65 terminal bracket also mounted on said stud and having a pair of terminals mounted thereon and extending laterally therefrom, said shell having an opening for admitting a connector plug to a position of association with said terminals and a guard for said terminals mounted on said shell,

said guard arching from a position in front of the terminals and then over the terminals and terminating at a position behind them, the side of said guard adjacent the bases of said terminals terminating at the shell and the opposite side 5 thereof being spaced from said shell to permit such association of said connector plug with said terminals, said shell having a countersunk portion opposite said guard to partially receive said connector plug. 10

13. In a sadiron construction, a sole plate, a shell therefor, a stud extending upwardly from said sole plate, a heating element for said sole plate, a cover plate for said heating element having a perforation receiving said stud, a nut to 15 retain said cover plate in position, said shell having a perforation receiving said stud, a retainer nut for said shell threaded on said stud and a terminal bracket also mounted on said stud and having a pair of terminals mounted thereon and 20 extending laterally therefrom, said shell having an opening for admitting a connector plug to a position of association with said terminals, said terminal bracket having a slot and tongue connection with said cover plate to retain the 25 terminal bracket against rotary movement about said stud.

14. In a sadiron construction, a sole plate, a shell mounted thereon, a terminal bracket, a stud extending upwardly from said sole plate through 30 said terminal bracket and shell, a spacer interposed between said terminal bracket and shell, a retainer nut on said stud to retain said shell, spacer and terminal bracket in position, said terminal bracket having a flange extending upwardly and lying in substantially the fore and aft vertical plane of the sole plate and a pair of terminal pins said flange being adapted to locate and support said pins with respect to position and direction so that they extend laterally with respect to said sole plate and at right angles to the plane of said flange, and means on said flange to locate it with respect to said shell. 35

15. In a sadiron construction, a sole plate, a shell mounted thereon, a terminal bracket, a stud 45 extending upwardly from said sole plate through said terminal bracket and shell, a spacer interposed between said terminal bracket and shell, a retainer nut on said stud to retain said shell, spacer and terminal bracket in position, said terminal bracket having a flange extending upwardly and lying in substantially the fore and aft vertical plane of the sole plate, a pair of terminal pins supported by said flange and extending laterally with respect to said sole plate, means on 50 said flange for locating it with respect to portions of the shell, said shell having an opening through which said flange and terminal pins extend, a portion of said shell adjacent said terminal pins being depressed and a guard portion on said shell 55 over said flange and terminal pins, said guard, in conjunction with said depressed portion of said shell, forming a socket to receive a connector plug.

16. In a sadiron construction, a sole plate, a shell therefor having its rear end overhanging the heel of said sole plate, a heating element for said sole plate, a cover plate for said heating element, said cover plate overhanging the heel of said sole plate and coacting with said rear end 70 of said shell to provide a bottom closure therefor beyond the heel of said sole plate.

HOWARD A. SMITH.
